DESIGN FOR A LIPSTICK HOLDER

Henriette Preller, Forest Hills, N. Y., assignor to Helena Rubinstein, Inc., New York, N. Y., a corporation of New York

Application October 2, 1941, Serial No. 103,612

Term of patent 7 years

To all whom it may concern:

Be it known that I, Henriette Preller, a citizen of the United States of America and residing in Forest Hills, New York, have invented a new, original, and ornamental Design for a Lipstick Holder, of which the following is a specification, reference being had to the accompanying drawing, forming part thereof.

I claim:

The ornamental design for a lipstick holder, as shown and described.

HENRIETTE PRELLER.
